UNITED STATES PATENT OFFICE.

WINTHROP L. JACOBS, OF JERSEY CITY, NEW JERSEY, ASSIGNOR TO HARTFORD CARPET COMPANY, OF HARTFORD, CONNECTICUT.

DESIGN FOR CARPET.

SPECIFICATION forming part of Design No. 12,205, dated March 29, 1881.

Application filed February 10, 1881. Term of patent 3½ years.

To all whom it may concern:

Be it known that I, WINTHROP L. JACOBS, of Jersey City, in the county of Hudson and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure A is a circular serrated figure with a square center, and has extending from it a branch, B, with flowers thereon. From the branch B projects a stem bearing upon it a rectangular figure, C, with pointed projections, while from the figure C projects another branch, D, with flowers thereon. Another stem growing from the figure A connects it with the palm-leaf figure E, and with the flower-like figure G, and also with the flowering branch H, all projecting from this same stem.

The figure I is a flower-like figure growing upon a stem, from which also projects the leaf-life figure J, the flowering branch K, and the flower-figure L, while from the figure I projects a stem, from which grow the star-shaped figure M and the oblong figure N. A stem projecting from the figure N connects it with the serrated figure O, (but partly shown,) which is, in turn, connected by a branching stem with the fan-shaped figure P and the circular figure Q.

The figure R is a palm-leaf figure, somewhat resembling in shape the figure E inverted, and is connected by a stem or band with the flowering branch S and with the circular figure T, which last has flower-like figures a b d e projecting from it, and is connected by another band with the tulip-like figure f, set on a stem projecting from the figure g, composed of a branch or spray of small closely-set flowers, which grows on a stem projecting from the circular rosette h.

The figures j and m resemble palm-leaves, and are somewhat similar in shape to the figures R and E.

The figure n is a branch projecting into the

design, having just below it the star-like figure p, which last is joined by a stem to the conical figure q.

U is a figure with horn-like projections, and is connected by a stem with the figure L.

V is a circular-patterned figure.

The figure h is like a circular flower, and g h and the bud-like figure t are connected by their stems.

A vine-like branch, X, with flowers and buds thereon, runs partly around the figure V.

The figure Y is a circular serrated figure, connected by a stem with the figure T, and having projecting from it several ball-shaped flowers set upon stems.

I claim—

1. The design for carpets, consisting of the figure A, substantially as shown.
2. The design for carpets, consisting of the figure B, substantially as shown.
3. The design for carpets, consisting of the figure II, substantially as shown.
4. The design for carpets, consisting of the figure G, substantially as shown.
5. The design for carpets, consisting of the figures G, II, A, B, and E, substantially as shown.
6. The design for carpets, consisting of the figure E, substantially as shown.
7. The design for carpets, consisting of the figure P, substantially as shown.
8. The design for carpets, consisting of the figure Q, substantially as shown.
9. The design for carpets, consisting of the figure V, substantially as shown.
10. The design for carpets, consisting of the figures t, h, f, and g, substantially as shown.
11. The design for carpets, consisting of the figure C, substantially as shown.
12. The design for carpets, consisting of the figures C and D, substantially as shown.
13. The design for carpets, consisting of the figure L, substantially as shown.
14. The design for carpets, consisting of the figure I, substantially as shown.
15. The design for carpets, consisting of the figure K, substantially as shown.
16. The design for carpets, consisting of the figure J, substantially as shown.

17. The design for carpets, consisting of the figures U, L, I, K, J, M, and N, substantially as shown.
18. The design for carpets, consisting of the figures p and q, substantially as shown.
19. The design for carpets, consisting of the figure R, substantially as shown.
20. The design for carpets, consisting of the figure S, substantially as shown.
21. The design for carpets, consisting of the figure M, substantially as shown.
22. The design for carpets, consisting of the figure Y, substantially as shown.
23. The design for carpets, consisting of the figures Y R S T, substantially as shown.
24. The design for carpets, consisting of the figures f and g, substantially as shown.
25. The design for carpets, consisting of the figures T a b d e, substantially as shown.
26. The design for carpets, consisting of the figure X, substantially as shown.
27. The design for carpets, consisting of the figures A, G, E, H, B, V, g, h, t, X, f, T, a, b, d, e, j, Y, R, S, m, Q, n, p, q, I, M, N, O, P, K, J, L, U, O, and D, substantially as shown.

WINTHROP L. JACOBS.
